POMPILIO MIANO, OF BRONX, NEW YORK.

COMBINATION KEY-CONTROLLED SLIDING-BOLT LOCK.

1,295,557.

Specification of Letters Patent. Patented Feb. 25, 1919.

Application filed September 25, 1917. Serial No. 193,135.

To all whom it may concern:

Be it known that I, POMPILIO MIANO, a citizen of the United States, residing at Bronx, in the county of New York and State of New York, have invented certain new and useful Improvements in Combination Key-Controlled Sliding-Bolt Locks, of which the following is a specification.

This invention relates to locks of the class requiring different movements of a key and knowledge of the particular manner of manipulating the key to enable the lock to be opened.

The object of the invention is to provide a simply constructed and efficient lock of this character which will reliably prevent those unacquainted with the combination from releasing the bolt thereby insuring safety to all doors equipped therewith.

Another object is to provide means whereby the simple turning of the key in backward direction will project the bolt into locked operative position where it will remain until again released by the correct manipulation of the key which controls the combination.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made without departing from the spirit of the invention.

In the accompanying drawings:—

Figure 1 represents a vertical section through a lock casing with the lock embodying this invention shown in front elevation therein and with the parts in locked operative position.

Fig. 2 is a vertical transverse section taken on the line 2—2 of Fig. 1 looking in the direction of the arrow *a*,

Fig. 3 is a similar view taken on the same line and indicated at 3—3 looking in the direction of the arrow *b*,

Fig. 4 is a longitudinal section taken on the line 4—4 of Fig. 1,

Fig. 5 is a side elevation of the key used in connection with this lock,

Fig. 6 is a longitudinal section through the key socket, and

Fig. 7 is an end elevation of the key.

In the embodiment illustrated, a rectangular casing 1 is shown comprising a rear wall 2 and a front wall 3, the latter having a right-angularly disposed integral flange 4 against which the rear wall of plate 2 is designed to fit as is shown clearly in Figs. 2, 3 and 4, said flange 4 operating as a spacer for the two plates. As is shown clearly in the figures above referred to, the meeting edges of plate 2 and flange 4 are beveled as shown at 5, to insure the close fitting of the parts. These plates are secured in locked position after the bolt members have been properly mounted therein by screws which pass through openings 6 in the rear wall plate and through corresponding openings, not shown, in the front plate, said screws after being so positioned having their heads burnished to remove all means for detaching them so that access to the interior of the lock is prevented, the parts after having once been placed therein being practically sealed. Spacing sleeves 7 preferably surround the apertures through which the fastening elements in plate 2 pass as is shown clearly in Figs. 1, 2, 3 and 4.

A locking bolt 8 is mounted to slide transversely through the casing 1 through openings 9 and 9' formed in the front and rear edges, respectively, said bolt being mounted within the casing in guides formed by straps or keepers 10 carried by the rear plate 2. This bolt 8 is provided near its front end in its upper edge with a square notch 11 and at a point spaced rearwardly therefrom with two beveled or inclined ratchet-like notches 12 and 13 for a purpose presently to be described. The lower edge of this bolt 8 is provided near its rear end with a notch 27 which is designed to receive when in projected operative position a locking finger 15 carried by a bolt or sliding catch 16 mounted to slide transversely relatively to bolt 8 in guides or keepers 17 carried by plate 2 as is shown clearly in Fig. 1. This bolt 16 is provided on its opposite edges with two series of teeth 18 and 19, the teeth 18 on the rear edge of the bolt being designed to be engaged by a spring pressed detent 20 mounted to slide in a keeper 21. This detent 20 is normally forced forward into projected position by a coiled spring 22 which bears at one end against the rear end of the detent and at its other end against a lug 23 carried by the rear end of the casing, a pin 110 carried by the rear end of the casing, a pin 110

24 being carried by said lug and projecting into said spring to operate as a guide therefor.

The bolt 16 is also forced normally toward bolt 8 by means of a coiled spring 25 mounted between a lug 26 projecting laterally inward from plate 2 and the rear end of said bolt 16, which latter has an upstanding flange 16' to prevent its being forced 10 through the lower keeper 17.

A forwardly extending finger 14 overlaps the bolt 16 extending transversely thereof as is shown clearly in Fig. 1 and under which is a spring 28 arranged longitudinally on the 15 outer face of said bolt 16 and against which said finger presses thereby operating to force the bolt toward plate 2 and prevents lateral movement thereof thereby insuring the engagement of the teeth of said bolt with said 20 spring pressed detent 21 on one side thereof and on the other side with a toothed pawl 29. This pawl 29 is pivoted at 30 on a stud which projects laterally from plate 2 and the rear end of said pawl is provided with 25 a plurality of teeth 29' which mesh with the teeth 19 at the front edge of bolt 16 so that when said pawl is arranged on said pivot the bolt 16 will be projected or retracted according to the direction in which the pawl is 30 turned. This pawl 29 tapers toward its front end and has a coiled spring 31 connected with a nose 32 thereof at a point spaced inwardly from its terminal, the other end of said spring being engaged with a 35 support here shown in the form of a split lug 33 projecting laterally inward from plate 2.

It will thus be seen that when the nose 32 of pawl 29 is raised against the tension 40 of spring 31 that the toothed end thereof which meshes with the teeth 19 of bolt 16 will operate to force said bolt downwardly against the tension of the expansion spring 25 and it may be held in this position by 45 the engagement of the detent 20 with one of the teeth 18 at the rear edge of the bolt 16, said detent thus operating to hold bolt 16 in retracted position with the finger 15 out of engagement with notch 14 of bolt 8. 50 Hence it will be obvious that in order that this bolt be held in retracted position by the detent 20 that a partial turn only must be given pawl 29 sufficient to cause the detent to spring into one of the teeth 18 of bolt 16.

Mounted for locking engagement with the ratchet shaped teeth 12 and 13 on the upper edge of the bolt 8 is a substantially S-shaped spring 34 having one end thereof 60 flattened as shown at 35 to form an attaching plate which is riveted to the rear wall 2 of the casing at a point near its upper end as is shown clearly in Fig. 1. The body portion of this spring which is made of a 65 heavy strip of resilient metal lies parallel

with the upper edge of bolt 8 and has one edge thereof cut out to form a locking tooth 36, the spring being curved downwardly at this point to adapt said tooth to snap into engagement with one of the recesses 12 70 or 13 in the bolt according to the position in which said bolt is located and as will be presently more fully hereinafter described. This spring 34 has a loop-shaped end 37 which lies against the upper face 75 of bolt 8 with one end 38 of the loop projecting beyond the lower edge of the bolt and disposed in the path of the wards of a key hereinafter to be described, so that when said key engages said loop, the spring 80 will be forced upwardly to release its tooth 36 from engagement with the recesses of bolt 8. This unlocking of spring 34 cannot however, be effected until the bolt is released from engagement with a spring 85 pressed catch 39 which is mounted to slide in a plane at right angles to the plane of movement of bolt 8 and to engage the recess 11 in its upper edge near the front thereof when the bolt is in projected operative position as is shown clearly in Fig. 1. This catch 39 is made in the form of a block mounted to slide in transversely spaced guides 40 and has a stud 41 projecting outwardly therefrom through a slot 90 42 in a head 43 carried by one end of a link 44. A coiled spring 45 is mounted in this slot and bears at one end against the stud 40 and at its other end against the outer wall of the slot, an overhanging finger 100 46 being provided to prevent the lateral displacement of said spring as is shown clearly in Figs. 1 and 3. It will thus be seen that this spring bearing against the stud 41 operates to force the catch 39 normally toward bolt 8 to adapt it to interlockingly engage with the recess 11 when said bolt is in operative projected position.

The link 44 has its lower end pivotally connected with a bolt 47 mounted to slide 110 in a plane at right angles to the path of movement of bolt 8, said bolt 47 being here shown guided in a keeper 48. This bolt 47 is provided on its front face with a projecting lug 49 for a purpose presently to 115 be described. The rear edge of this bolt has a series of teeth 50 with which mesh the teeth 51 of a pawl 52 pivoted on a stud 53 projecting laterally from plate 2. This pawl 53 tapers toward its rear end and 120 has a coiled spring 54 connected at one end thereof at a point spaced inwardly from the nose 55 thereof, the other end of said coiled spring being anchored on a split stud 56 projecting laterally from plate 2. 125

A plate spring 57 is anchored at one end to a split stud 58 carried by plate 2 and has its other end bent laterally inward to form a hook-shaped head 59 which is designed to bear on the projecting lug 49 130

when the bolt 47 is in locked position and to spring under said projection when the bolt is in raised position thereby yieldably holding said bolt in raised position. The 5 raising of this bolt 47 is accomplished by means of the turning of the pawl 52 which is actuated by a key presently to be described. By an inspection of Fig. 1 it will be obvious that when the nose 55 of pawl 52 is moved downwardly the toothed end thereof will move up and thereby carry with it bolt 47 which, through the link 44 will operate to raise catch 39 sufficiently to cause it to clear the recess 11 in bolt 8. 10 When this bolt 47 is so raised the head 59 of spring 57 will spring under the projection 49 and hold bolt 47 in raised position with the catch 39 held thereby out of engagement with bolt 8. It will thus be seen that when the finger 15 of bolt 16 and the catch 39 controlled by bolt 47 are out of engagement with the recesses 11 and 14 of bolt 8 that the spring 34 may then be released from its locking engagement 15 with bolt 8 by the upward movement of loop 38 which is accomplished by a key presently to be described, and simultaneously with the lifting of this loop a slight rearward movement is imparted to bolt 8 so that the recessed portion thereof passes beyond the tooth 36 of spring 34 thereby preventing said tooth from locking the bolt. The bolt 8 may then be retracted in a manner presently to be described. 20 Oppositely disposed keyholes as 60 are formed in both plates 2 and 3 at a point midway between the noses 32 and 55 of the pawls 29 and 52 as is shown clearly in Fig. 1, the slots of said keyholes being disposed 25 downwardly as shown. Rotatably mounted in the upper end of the keyholes is a sleeve 61 having annular shoulders 62 and 63 spaced inwardly from the opposite ends thereof as is shown clearly in Fig. 6 and 30 which are designed to engage the inner faces of plates 2 and 3 and operate as stops so that said sleeve will be held in position with its ends mounted to rotate in said keyholes. A pintle 64 extends longitudinally through 35 this sleeve 61 and is held in centered position therein by means of a pin 65 which extends between pintle 64 and said sleeve at a point opposite the opening or slot 66 which extends from top to bottom of the sleeve at 40 the front end thereof and across which is a pin 67 which is also secured to the pintle 64. It will thus be seen that this pintle 64 is rigidly anchored within the slot and is designed to receive a key 68 shown in Fig. 5. 45 This key 68 has a slot 69 extending inwardly from a point opposite the ward 70 thereof and this slot 69 when the key is engaged with the pintle 64 is designed to fit over the pin 65 so that the key will be securely connected with the sleeve and the turning of 50

said key will thus operate to turn the sleeve with it, the key being insertible from either side of the lock casing.

The bolt 8 is also provided in its lower edge with a plurality of recesses 75, three 70 of which are here shown and between which are disposed triangular teeth or projections 74 with the inclined walls of which the wards of the key 68 are designed to engage for projecting and retracting the bolt in a manner 75 hereinafter to be described.

In the operation of this lock, with the parts shown in the position indicated in Fig. 1, in which position the bolt 8 is in projected locking position, and is held locked by the 80 finger 15, catch 39 and tooth 36 of spring 34, to release said bolt 8 and permit its withdrawal, the key 68 is first inserted through the key hole 60 and is turned to the left. This turning will cause the terminal 85 71 of the bit of the key which has a groove 72 formed transversely thereof at the base of said terminal and which is designed to pass over the arcuate guide lug 73 projecting from plate 2 to engage the lower edge of 90 nose 32 of pawl 29. This turning is continued until said nose is forced upwardly a sufficient distance against the tension of spring 31 to cause the lowering of bolt 16 a sufficient distance to bring the detent 20 into 95 locking engagement with the next tooth above that with which it is engaged and this movement will be indicated by a slight click. When this click is heard the turning of the key should be stopped. The key 68 is then 100 turned toward the right until it passes the nose 55 of pawl 52 forcing downwardly the bolt 47 which operates to move catch 39 into recess 11. The key is then continued in its upward turning by turning toward the right 105 which causes the terminal 71 of its ward to engage the loop 38 of spring 34 and forces said spring upwardly, at the same time permitting said terminal to engage one of the teeth on the lower edge of the bolt 8 and move said bolt a sufficient distance to disengage the tooth 36 of spring 34 from its engagement with the recess 13 and permit it to drop into the front recess 12. The key is 110 then turned again toward the left bringing the terminal 71 of its ward into engagement with the outer face of nose 55 of pawl 52 and rocking said nose causing the teeth 51 thereof to raise bolt 47 a sufficient distance to remove catch 39 out of recess 11 and when the bolt reaches this position the head 59 of the spring 57 will extend inwardly under the projection 49 and thus hold said bolt and catch in raised position. The key 68 is then 115 turned again toward the right bringing the ward terminal 71 again into engagement with the loop 38 raising said loop and the body portion of the spring with which it is connected a sufficient distance to disengage the tooth 36 from the front recess 12 in bolt 120 125 130

8. Simultaneously with the raising of this loop 38 the ward of the key is brought into engagement with one of the projections on the lower edge of bolt 8 thereby moving said bolt inwardly and positioning the tooth 36 of the spring 34 on the upper edge thereof so that said bolt may then be readily retracted by the continued turning of the key 68 to the left. Several turns of this key will be necessary in order to completely retract bolt 8 which is accomplished by the engagement of the ward of said key with the recesses 75 in the lower edge of bolt 8.

When it is desired to again lock or project bolt 8 the key 68 is turned toward the right a sufficient number of times to completely project bolt 8 into locking position, which when it reaches said position will bring the recesses 14 and 11 opposite finger 15 and 20 catch 39 respectively and these elements under the tension of their springs will spring into locking engagement with said recesses. The tooth 36 will also drop into locking engagement with the recess 13 at the top of the 25 bolt and said bolt will be locked in projected position until the key is again manipulated in the manner above described.

It is to be understood that the combination here shown may be changed by arranging the movable parts of the device so as to make it necessary to move the bolt 16 downwardly two or more notches before causing the complete withdrawal of this finger 15 from its recess 14, or by varying the number 30 of notches or recesses in the upper edge of the bolt with which the tooth 36 of spring 34 engages or by changing the construction and operation of the pawl 52 and bolt 47 so as to render it necessary to swing said 35 pawl upon its pivot several times before completely disengaging catch 39 from the recess 11 of bolt 8.

From the foregoing description, taken in connection with the accompanying drawings, the advantages of the construction and of the method of operation will be readily apparent to those skilled in the art to which the invention appertains and while I have described the principle of operation of the 40 invention together with the device which I now consider to be the best embodiment thereof, I desire to have it understood that the device shown is merely illustrative and that such changes may be made as are within 45 the scope of the claimed invention.

I claim:

1. In a key controlled combination lock, an inclosing casing, a locking bolt slideable into and out of said casing, spring pressed 50 means operable from opposite edges of said bolt to interlockingly engage therewith, pawl actuated means for disengaging said spring pressed means from said bolt and arranged on one side of said bolt, and a key 55 for operating said pawls.

2. In a key controlled combination lock, an inclosing casing, a locking bolt slideable into and out of said casing, a pair of plates movable toward and away from said locking bolt on opposite sides thereof, coöoperating 70 interlocking elements carried by said locking bolt and by said last mentioned plates whereby said locking bolt is held in projected position, key controlled means for retracting said plates from engagement with 75 said locking bolt, and means for holding said plates in released position.

3. In a key controlled combination lock, an inclosing casing, a main locking bolt slideable into and out of said casing, spring projected catches movable in a plane at right angles to the plane of movement of said bolt for locking the bolt in projected position, a key, and means operable by the oscillation of said key to disengage said catches. 80

4. In a key controlled combination lock, an inclosing casing, a main locking bolt slideable into and out of said casing, spring projected catches movable in a plane at right angles to the plane of movement of said bolt 90 for locking the bolt in projected position, one of said catches having teeth on its opposite sides, a spring projected detent for engaging a tooth on one side and locking said catch in retracted position, a pawl 95 pivoted intermediately of its ends on the other side of said catch with teeth on one end meshing with the teeth of the catch and a nose on its other end, a spring engaging the nose of said pawl for holding 100 its toothed end engaged with said catch and for returning it after actuation, a pawl connected to release the other catch and a key adapted to be positioned to actuate said pawls on the oscillation thereof to disengage 105 said catches from said bolt.

5. In a key controlled combination lock, an inclosing casing, a main locking bolt slideable into and out of said casing, spring projected catches movable in a plane at right 110 angles to the plane of movement of said bolt for locking the bolt in projected position, one of said catches having teeth on its opposite sides, a spring projected detent for engaging a tooth on one side and locking said 115 catch in retracted position, a pawl pivoted intermediately of its ends on the other side of said catch with teeth on one end meshing with the teeth of the catch and a nose on its other end, a spring engaging the nose of said 120 pawl for holding its toothed end engaged with said catch and for returning it after actuation, a pawl connected to release the other catch, a key adapted to be positioned to actuate said pawls on the oscillation 125 thereof to disengage said catches from said bolt, and means on said bolt for engagement by said key to withdraw it on the release thereof from said catches.

6. In a key controlled combination lock, 130

an inclosing casing, a main locking bolt slideable into and out of said casing, spring projected catches movable in a plane at right angles to the plane of movement of said bolt
 5 for locking the bolt in projected position, a toothed member slideable in said casing opposite said catch on the other side of said bolt, a link connecting said catch and member, a toothed pawl meshing with the teeth of said
 10 member, a coiled spring connected with the nose of said pawl to hold said catch normally in engaged position, a pawl controlling the other catch, and a key adapted to be positioned to actuate said pawls on the
 15 oscillation of the key to disengage said catches.

7. In a key controlled combination lock, an inclosing casing, a main locking bolt slideable into and out of said casing, spring projected catches movable in a plane at right angles to the plane of movement of said bolt for locking the bolt in projected position, a toothed member slideable in said casing opposite said catch on the other side of said bolt,
 20
 25 a link connecting said catch and member, a toothed pawl meshing with the teeth of said member, a coiled spring connected with the nose of said pawl to hold said catch normally in engaged position, the other catch having teeth on its opposite sides, a spring projected detent for engaging a tooth on one side and locking said catch in retracted position, a pawl pivoted intermediately of its ends on the other side of said catch with
 30 teeth on one end meshing with the teeth of the catch and a nose on its other end, a spring engaging the nose of said pawl for holding its toothed end engaged with said catch and for returning it after actuation,
 35
 40 and a key adapted to be positioned to actuate said pawls on the oscillation of the key to disengage said catches.

8. In a key controlled combination lock,

an inclosing casing, a main locking bolt slideable into and out of said casing, spring projected catches movable in a plane at right angles to the plane of movement of said bolt for locking the bolt in projected position, 45 said bolt having ratchet teeth on its upper edge, a spring anchored at one end to said casing with its body portion resting on the upper edge of said bolt and provided with a tooth for locking engagement with said ratchet teeth, a rotary key actuated member, and controlling means for the locking spring 50 and catches positioned in the path of said key whereby said bolt locking spring and catches are disengaged from the bolt on the proper manipulation of the key.

9. In a key controlled combination lock, 60 an inclosing casing, a main locking bolt slideable into and out of said casing, spring projected catches movable in a plane at right angles to the plane of movement of said bolt for locking the bolt in projected position, 65 said bolt having ratchet teeth on its upper edge, a spring anchored at one end to said casing with its body portion resting on the upper edge of said bolt and provided with a tooth for locking engagement with said 70 ratchet teeth, said spring having an extension arranged on the outer face of said bolt and projecting below its lower edge, a rotary key actuated member, a key for connection with said member, catch releasing means located in the path of movement of the key bit, said spring extension being also located in said path, and means on the bolt whereby a predetermined turning of the key will operate to release said bolt and to retract it. 75 80

In testimony whereof I affix my signature in presence of two witnesses.

POMPILIO MIANO.
